Patented May 28, 1918.

Inventor,

Joseph E. Vincent;

By
A. B. Upsham
Attorney.

UNITED STATES PATENT OFFICE.

JOSEPH E. VINCENT, OF CAMBRIDGE, MASSACHUSETTS.

PETAL-FORMER.

1,267,939.

Specification of Letters Patent. Patented May 28, 1918.

Application filed April 17, 1917. Serial No. 162,614.

To all whom it may concern:

Be it known that I, JOSEPH E. VINCENT, a citizen of the United States, and a resident of Cambridge, in the county of Middlesex and Commonwealth of Massachusetts, have invented certain new and useful Improvements in Petal-Formers, of which the following is a full, clear, and exact specification.

10 In the manufacture of paper flowers, it is found that by pressing a smooth body along a tissue paper petal supported upon a yielding surface, the paper will acquire the crinkled form desired for the imitation of 15 chrysanthemum blossoms. To this end I have devised a tool comprising a shank, a slender neck and a spherical head for the better treatment of the paper petals; and I have further improved thereon by providing 20 mechanism for automatically actuating a plurality of such tools simultaneously, and thereby both accelerating the work and rendering it more uniform.

Referring to the drawings forming part 25 of this specification, Figure 1 is a side elevation, partly in section, showing a machine embodying my improvements. Fig. 2 is a face view of one of the tissue paper petals to be treated. Fig. 3 is a detail 30 view of one of the petal-treating members.

I prefer to act upon several petal-blanks 1 at a time, laid one upon another upon a soft rubber surface 2. Fixed above this surface is a suitable support, as the bracket 3, 35 from which depends a rod 4 having at its lower end ears 5 to which are pivoted tubular levers 6. Slidable in each tubular lever is the shank 7 of one of the petal-treating tools, the latter comprising the shank, a neck 9 and a spherical head 10. A pin 11 projecting from the shank into a slot 12 prevents the tool from dropping out from the tubular lever 6, while permitting the desired longitudinal movement therein, a helical spring 13 pressing each tool down and 45 outward.

At the upper end of each lever 6 is an antifriction roll 14 engaging a cone 15 slidable on the rod 4, the cone being elevated 50 and depressed by any suitable means, as the lever 16 connected therewith by a link 17. Leaf springs 19 bearing outwardly against

the levers 6 yieldingly swing them away from a common center.

The bracket 3 being elevated or the table 55 20 being lowered, to permit a suitable quantity of petals 1 to be put in place, and the cone 15 being slid upward on the rod 4, the tool-heads 10 are brought into engagement with the tips of the petals by raising the 60 table or depressing the bracket, until the springs 13 are partially compressed.

The cone 15 is now forced downward, thereby causing the spherical heads 10 to be moved toward each other. This movement of the heads, while pressing down upon the tissue paper, with their yielding supporting surface 2, acts to produce in the thin tissue the crinkled effect desired, the petals being not only crinkled but caused 70 to curl upward in the manner closely imitating the flower above referred to.

As shown in Fig. 3, the shank 9 does not join radially to its head 10, but tangentially, in order to permit each petal as it is acted 75 upon to curl up over the head.

What I claim is:

1. A flower forming instrumentality comprising a plurality of shanks each having a rounded head at its lower end, a pivoted 80 tubular lever slidably receiving each shank, a helical spring in each tubular lever pressing the shank therein downward, a yielding surface for the paper blanks, and means for simultaneously moving the tubular levers 85 to slide the heads along the paper blanks toward each other.

2. A flower forming instrumentality comprising a stationary rod, a plurality of tubular levers intermediately pivoted to its lower 90 end, a shank having a rounded lower end slidably located in each tubular lever, resilient means pressing the said shanks downward, a cone slidable on the rod to force the upper ends of the tubular levers outward and the rounded heads toward each other, means for thus moving the cone, and a soft surface for supporting the paper 95 blanks beneath the rounded heads.

3. A flower forming instrumentality comprising a plurality of tubular levers each having an anti-friction roll at its upper end, a stationary rod having said levers pivoted at an intermediate point of each to its 100

lower end, springs for pressing the lower ends of the levers away from each other, a shank having a rounded lower head slideable in each tubular lever, a spring in each lever pressing the shank therein downward, means for limiting the outward movement of each shank from its tubular lever, and a

cone forcibly slideable on said rod for moving the lower ends of the levers toward each other.

In testimony that I claim the foregoing invention, I have hereunto set my hand this 31 day of March, 1917.

JOSEPH E. VINCENT.
